3 Claims

Matter enclosed in heavy brackets **1** appears in the original patent but forms no part of this reissue specification; matter printed in italics indicates the additions made by reissue.

My invention relates to the combination of an electric light bulb having a filament with a magnet to move the filament into vibration to simulate the flickering of a flame of a candle.

It is among the objects of my invention to attach or associate a magnet within, to or with an electric light bulb having a filament, so as to oscillate the filament into vibration to simulate the flickering of a flame of a candle.

My invention also contemplates such other objects, advantages and capabilities as will later more fully appear, and which are inherently possessed by my invention.

While I have shown in the accompanying drawings a preferred embodiment of my invention, yet it is to be understood that the same is susceptible of modification and change without departing from the spirit of my invention.

Referring to the drawings, FIG. 1 is a top plan view; FIGS. 2 and 3 are vertical elevational views at right angles to each other; FIG. 4 is a vertical sectional view; FIG. 5 is a bottom plan view of the preferred form of my electric light bulb with oscillating filaments; and FIG. 6 is a vertical elevational view of a modified form of my device.

The embodiment selected to illustrate my invention comprises an electric light bulb **10** having a closed transparent elongated glass body member **11** having at its lower portion a threaded part **12** spaced from a bottom electrical contact portion **13** by an insulated portion **14**. Extending upwardly from said contact portion **13**, within body member **11** is one leg **15** of filament **16**. The other leg **17** of filament **16** extends to threaded part **12**. Legs **15** and **17** of filament **16** are attached to glass stem press **18** supported on contact portion **13** and have enlarged extensions **19** and **20** therebeyond. An elongated loop portion **21** extends upwardly within body member **11** and connects extensions **19** and **20**. Loop portion **21** converges to a curved upper end **22**. Filament **16** is preferably made of carbon.

Positioned within loop **21** in body member **11**, support pin **23** has its lower end mounted centrally into stem press **18**. The upper end of support pin **23** is curved to support and is spot welded to cylindrical magnet **24**, which is positioned at right angles to the axis of stem press **18**.

In use when bulb **10** is screwed into an electric light socket leading to an electrical source of A.C. current, contact portion **13** receives electricity which is communicated to filament **16** to light up incandescent loop portion **21**. Magnet **24** moves loop portion **21**, and the electric current moves it back so that there is a continuing oscillating or vibrating of loop portion **21**. This

2

provides a moving lighted loop portion which simulates the flickering of a flame of a candle.

While I prefer as heretofore set forth to house my magnet **24** within the body portion **11** of the bulb **10**, yet my magnet **24** may be attached to the exterior of the bulb, and if increased in magnetic power be positioned in sufficient proximity to the bulb to operate the filament and make it move.

As shown in FIGS. 1—4 of the drawing, the filament **16** includes only a single loop **21**, and this loop lies generally in a plane. Magnet **24** is a cylindrical magnet and is supported so that its major axis is generally normal to the plane of the loop and so that the magnet **24** is intersected by the plane of the loop **21**. The single loop **21** is disposed so that all portions of the filament are spaced from the magnet **24** and the pin **23**.

Having thus described my invention, I claim:

1. An electric light bulb having a filament as the only movable part, said filament adapted to be illuminated when said bulb is attached to a source of A.C. electrical current, said bulb having a stem mounted therein, a support pin mounted on said stem and a magnet attached to said support pin adjacent said filament to provide direct movement of the illuminated filament and with return movement set up by the A.C. electrical current to maintain continuing vibration of the illuminated filament simulating a flickering flame of a candle. **1**

2. An electric light bulb having a filament as the only movable part, said filament adapted to be illuminated when said bulb is attached to a source of A.C. electrical current, said bulb having a stem mounted therein, a support pin mounted on said stem and a magnet attached to said support pin adjacent said filament to provide direct movement of the illuminated filament and with return movement set up by the A.C. electrical current to maintain continuing vibration of the illuminated filament simulating a flickering flame of a candle, said filament consisting essentially of a single loop with all portions thereof spaced from said magnet and said pin, at least a substantial portion of said filament lying generally in a plane, said magnet having a major axis disposed generally normal to said plane, and said plane intersecting said magnet.

3. The bulb of claim 2, said filament comprising a carbon filament.

4. The bulb of claim 2, said magnet being attached to said pin by a spot weld.
